(57) **CLAIM**

The ornamental design for a vehicle front bumper cover, shown and described.

DESCRIPTION

FIG. 1 is a top plan view of a vehicle front bumper cover; FIG. 2 is a bottom plan view of the vehicle front bumper cover;

FIG. 3 is a front elevational view of the vehicle front bumper cover;

FIG. 4 is a left side elevational view of the vehicle front bumper cover;

FIG. 5 is a perspective view of the vehicle front bumper cover; FIG. 6 is another perspective view of the vehicle front bumper cover;

FIG. 7 is a rear elevational view of the vehicle front bumper cover; and,

FIG. 8 is a right side view of the vehicle front bumper cover. The vehicle front bumper cover is styled independently of adjacent vehicle panels. Shading is used to illustrate the curvature of the part and not color. Any functional features of the vehicle front bumper cover are not claimed. Views are photographs of a vehicle front bumper cover. The various views are not necessarily to scale in order to better illustrate the design.
